UNITED STATES PATENT OFFICE

2,378,076

PISTON

Herbert H. Freeman, Minneapolis, Minn.

Application February 23, 1944, Serial No. 523,524

2 Claims. (Cl. 309—6)

My invention relates to an improvement in pistons for internal combustion engines, altho applicable, too, to steam engines, and the object of said invention is to permit pressure from the combustion chamber of such engines to be introduced into the packing-ring grooves of such engine pistons in such manner as to press the packing-rings firmly against the engine cylinder walls, as shown in the accompanying drawing, in which like numerals refer to like parts throughout the drawing, in which

Fig. 1 is a plan or top view, and Fig. 2 a side elevation, partly in section, of my invention; Fig. 3 is an enlarged sectional view of Fig. 2 to show more clearly the rotation of pressure-plug 6 to channel or port 2. 1 being the piston-head; 2, ports connecting the compression chamber with the piston-ring grooves via elbow 4 so that the gas pressure may push against the piston rings (see Fig. 3); 3, reinforcing of piston walls around said ports. An important feature of this arrangement lies in the fact that only compressed air reaches the lower, free-from-carbon, walls of said ports and therefore the upper walls are automatically freed from combustion residue at each exhaust. Fig. 3 is an enlarged view of port channel 2 showing a snug-fitting but freely movable pressure-plug 6, the inner, or channel end of said plug being tapered to permit free passage of compressed air to the ring-grooves below. The pur-

pose of this plug 6 is to limit and confine the pressure against the inner surface of the packing-ring to the area of such plug-end and not permit pressure to seep around the entire inner circumference of the ring 5.

I claim:

1. In a piston having a port or ports connecting the cylinder combustion chamber with packing-ring grooves in said piston, a movable plug in said port or ports by means of which the application of compression chamber pressure to the inner surface of piston packing-rings is limited to an area approximately that of a cross section of said plug.
2. A piston having ports or channels connecting the cylinder combustion chamber with the packing-ring grooves of such piston in such manner that any pressure in said combustion chamber may be wholly or in part applied to the inner or piston side of the packing rings thus forcing or expanding said rings, each in its own groove, against the complementary cylinder wall, the pressure admitted to said rings to be regulated by the size of the port or ports admitting such pressure to said ring or rings as the engine-duty may require, such pressure freely open, through aforesaid channels, to exhaust with the combustion chamber pressure, such rings being free to expand under such pressure until worn too thin for safety.

HERBERT H. FREEMAN.

CERTIFICATE OF CORRECTION.

Patent No. 2,378,076.

June 12, 1945.

HERBERT H. FREEMAN.

It is hereby certified that error appears in the printed specification of the above numbered patent requiring correction as follows: Page 1, first column, line 15, for "rotation" read --relation--; and that the said Letters Patent should be read with this correction therein that the same may conform to the record of the case in the Patent Office.

Signed and sealed this 13th day of November. A. D. 1945.
